US00D526277S

(12) **United States Design Patent** (10) **Patent No.:** **US D526,277 S**
Wu (45) **Date of Patent:** **** Aug. 8, 2006**

(54) **INTERFACE OF AN ELECTRICAL CONNECTOR**

(75) Inventor: **Jerry Wu**, Irvine, CA (US)

(73) Assignee: **Hon Hai Precision Ind. Co., Ltd.**,
Taipei Hsien (TW)

(**) Term: **14 Years**

(21) Appl. No.: **29/211,229**

(22) Filed: **Aug. 11, 2004**

Related U.S. Application Data

(63) Continuation-in-part of application No. 10/456,369, filed on Jun. 6, 2003, now Pat. No. 6,942,524.

(51) **LOC (8) Cl.** **13-03**

(52) **U.S. Cl.** **D13/147**

(58) **Field of Classification Search** **D13/133, D13/146-147, 184, 199; 439/62, 79, 108, 439/260, 329, 375, 422, 495, 499, 607, 637-639**

CLAIM

The ornamental design for an interface of an electrical connector, as shown and described.

DESCRIPTION

FIG. 1 is a top perspective view of an interface of an electrical connector, showing my new design; and, FIG. 2 is a top plan view thereof.

The broken line showing of the environment is for illustrative purposes only and forms no part of the claimed design.

1 Claim, 2 Drawing Sheets

FIG. 1

FIG. 2
